T. R. AUSTIN,
EGG TESTER,
APPLICATION FILED OCT. 2, 1918.

Patented Apr. 22, 1919.

Inventor:

T.R. Austin

By Watson E. Coleman
Attorney

UNITED STATES PATENT OFFICE.

THOMAS R. AUSTIN, OF ICONIUM, MISSOURI.

EGG-TESTER.

1,301,086.

Specification of Letters Patent. Patented Apr. 22, 1919.

Application filed October 2, 1918. Serial No. 256,576.

To all whom it may concern:

Be it known that I, THOMAS R. AUSTIN, a citizen of the United States, residing at Iconium, in the county of St. Clair and State 5 of Missouri, have invented certain new and useful Improvements in Egg-Testers, of which the following is a specification, reference being had to the accompanying drawings.

10 This invention relates to certain improvements in egg testers, and it is an object of the invention to provide a device of this general character having novel and improved means whereby the rays of the sun 15 may be employed to candle an egg. It is also an object of the invention to provide a novel and improved device of this general character which, when not in use, may be folded or compacted to occupy a minimum 20 of space.

Another object of the invention is to provide a device of this general character including novel and improved means whereby rays of light, particularly those emitted 25 from the sun, may be directed or reflected to penetrate a suitably positioned egg in order to disclose all blood veins, spots, and specks which may be within the egg, and also to determine the fertility of the egg.

30 The invention consists in the details of construction and in the combination and arrangement of the several parts of my improved egg tester whereby certain important advantages are attained and the device rendered simpler, less expensive, and otherwise 35 more convenient and advantageous for use, as will be hereinafter more fully set forth.

The novel features of my invention will hereinafter be definitely claimed.

40 In order that my invention may be better understood, I will now proceed to describe the same with reference to the accompanying drawings, wherein:

Figure 1 is a vertical sectional view taken 45 through an egg tester constructed in accordance with an embodiment of my invention and assembled for use; and

Fig. 2 is a fragmentary view partly in top plan and partly in section illustrating 50 the lowermost frame and the supporting means coacting therewith for the reflector.

As disclosed in the accompanying drawings, A denotes a frame, preferably oblong, and which has secured thereto and disposed 55 over the outer face thereof a plate 1 of suitable material.

Hingedly connected as at 2 with one end of the frame A is a second frame B of a form coincident with the configuration of the frame B, and secured to and overlying 60 the outer face of the frame B is a plate 3 of opaque material, and which is provided at substantially its center with an egg receiving opening 4. Hingedly connected as at 65 5 with the opposite end portion of the frame B is a third frame C of the same configuration as the frame B, and secured to and overlying the outer face of the frame C is a plate 6 also of opaque material. Connecting the longitudinal sides of the frames B and C are 70 the flexible curtains or walls 7 whereby a dark room is afforded when the frames B and C are in separated relation.

When not in use the frames A, B, and C are adapted to be folded one upon the other 75 with the flexible curtains or side walls 7 extending, if desired, between the frames B and C.

The resultant spaces between the frames A and B, when folded one upon the other, afford 80 a chamber or compartment in which certain of the parts comprised in my improved tester may be stored. The outer end of the frame B is provided with a suitable fastening member 8 coacting with the corresponding end of the frame A for locking 85 said frames A and B in their folded or closed relation, while the outer end of the frame C is also provided with a suitable fastening member 9 also coacting with the opposite end portion of the frame A for holding 90 the frame C in its folded or closed position. The hinged end portion of the frame C is provided with a hand grasp 10 to afford means whereby the device may be 95 readily transported.

In order to maintain the frame B in an open position relative to the frame A, I have pivotally engaged at one end portion with a side of the frame B a rigid arm or 100 link 11. The opposite or free end portion of the arm or link 11 is adapted to seat within one of a series of longitudinally spaced notches or recesses produced in the adjacent side of the frame A. By this 105 means it will be at once self-evident that the frame B may be held at different angles relative to the frame A. In order to maintain the frames B and C in the desired separated relation, I have pivotally engaged 110 with the frame C an end portion of a rigid arm or link 14 which coacts with a series 12

of notches or recesses 15 produced in the adjacent side of the frame B for the same purpose as has hereinbefore been stated relative to the arm or link 11 and the notches 5 or recesses 12.

M denotes a base member adapted to be positioned upon the plate 1 when the device is adjusted for use, and said member consists of two elongated sections 16 hingedly 10 connected at one end as at 17 for relative lateral swinging movement, and the opposed faces of the sections 16 are provided with recesses 18 which coact to afford a socket to receive a ball 19 carried by the 15 lower end portion of a supporting arm 20. Disposed through the free end portions of the sections 16 of the base member M is a bolt 21 having threaded on its free end portion of its shank a thumb nut 22. Immediately adjacent the thumb nut 22 and mounted upon the bolt is a washer 23. Surrounding the bolt 21 and interposed between the washer 23 and the outer side face of the adjacent section 16 is a rubber gasket 24, 20 which serves to constantly urge the adjacent sections 16 one toward the other in order to maintain pressure upon the ball 19 to permit said ball to have easy movement in its socket 18 when it is desired to adjust the arm 20 for a purpose which will hereinafter 25 be more particularly referred to.

The opposite or upper end portion of the arm 20 is provided with a socket 25 in which seats a shank 26 extending outwardly 30 from the reflector 27 at substantially its axial center. As herein disclosed the reflector 27 is concavo-convex in form with its concave face upwardly disposed in a direction away from the shank 26.

40 Upon proper adjustment of the reflector 27 relative to the opening 4 in the plate 3,

the solar rays may be focused directly on an egg seated within the opening 4 with the result that the operator may readily and conveniently candle the egg to discover all 45 blood veins, spots, and specks in the egg, and to determine the fertility thereof. It will also be understood that with the use of my improved egg tester, the operator is not confined but is at all times in a position to 50 inhale fresh air.

When the device is not in use the reflector 27 and its concomitant parts may be readily separated so that the same can be stored within the compartment or chamber afforded 55 between the frames A and B when in compacted or folded relation.

I claim:

1. A reflecting device for an egg tester comprising a base member consisting of two 60 hingedly connected sections, yielding means constantly urging the sections one toward the other, an arm having an end portion clamped between the sections and capable of swinging movement, and a reflector carried 65 by said arm.

2. A reflecting device for an egg tester comprising a base member consisting of two hingedly connected sections, yielding means constantly urging the sections one toward 70 the other, an arm having an end portion clamped between the sections and capable of swinging movement, the opposite end portion of the arm being provided with a socket, and a reflector provided with a shank 75 seatable within the socket of the arm.

In testimony whereof I hereunto affix my signature in the presence of two witnesses.

THOMAS R. AUSTIN.

Witnesses:

H. C. AUSTIN,

C. L. PARKS.
